UNITED STATES PATENT OFFICE.

SOLON G. HOWE, OF DETROIT, MICHIGAN, ASSIGNOR OF ONE-HALF TO
JEROME W. HYDE, OF SPRINGFIELD, MASSACHUSETTS.

SEWING-MACHINE.

SPECIFICATION forming part of Letters Patent No. 644,174, dated February 27, 1900.

Application filed November 19, 1897. Serial No. 659,088. (No model.)

To all whom it may concern:

Be it known that I, SOLON G. HOWE, a citizen of the United States, residing at Detroit, county of Wayne, State of Michigan, have invented certain new and useful Improvements 5 in Sewing-Machines; and I declare the following to be a full, clear, and exact description of the invention, such as will enable others skilled in the art to which it appertains to 10 make and use the same, reference being had to the accompanying drawings, which form a part of this specification.

This invention relates to certain new and useful improvements in sewing-machines, the 15 machine being more especially adapted for heavy work and for an overstitching-machine.

The invention consists of the structure, combination, and arrangement of devices 20 hereinafter described and claimed, and illustrated in the accompanying drawings, in which—

Figure 1 is a vertical section of a machine on the line 1 1, Fig. 5, embodying features of 25 the invention. Fig. 2 is a plan view of portions of the machine, the cover being removed and showing parts in horizontal section. Fig. 3 is a section on the line 3 3, Fig. 1. Fig. 4 is a detail view showing one face of the cam 30 E². Fig. 5 is a view in section on the line 5 5, Fig. 1. Fig. 6 is a vertical section on the line 6 6, Fig. 2. Fig. 7 shows detail views of the lever F² with related parts in section. Fig. 8 is a partial vertical section through the rear 35 of the pressure-arm. Fig. 9 is a partial vertical section on the line 10 10, Fig. 8. Fig. 10 is a detail view of the portion D' of the needle-bar. Fig. 11 is a front view of said portion of the needle-bar. Fig. 12 is a section on 40 the line 13 13, Fig. 10. Fig. 13 is a detail view showing one of the boxes for carrying the inner ends of the driving-shaft. Fig. 14 is a side elevation of the feeding-case. Fig. 15 is a vertical section of the same. Fig. 16 45 is an end view, partly in section, showing the device for registering the measurements of the stitch. Fig. 17 is a plan view of the same. Fig. 18 is an end view of a locking device for preventing the feed-screw from changing the 50 feed while in operation. Fig. 19 is a perspec-

tive view of the case of the machine, the cap or top being removed. Fig. 20 is an end view of the machine-table and the truck to carry the carpet. Fig. 21 is a sectional view of one of the clamping devices. Fig. 22 is a plan 55 view of a modified form of clamping device. Fig. 23 is a plan view of the table, machine, and carrying device. Fig. 24 is a sectional view showing the joint of one form of clamping lever-arm. Fig. 25 is a side elevation of 60 a modified form of clamping lever-arm, showing a supplementary clamping-arm, partly in section. Fig. 26 is a partial plan view showing the parts in section of a tripping-lever for tripping the pinion meshing with the rack 65 that carries the table. Fig. 27 is a detail view of the cap A¹² and the locking-nut thereupon. Fig. 28 shows details of the construction of the needle-bar. Fig. 29 is a detail view, in front elevation, showing the lever A⁶ and related parts. Fig. 30 is a detail view of a spring-70 clamp to hold the edges of the work together. Fig. 31 is a detail view of a work-clamp. Fig. 32 is a sectional view showing a modification 75 in the manner of forming the joint of one of the standards upon the traveling platform with the base or bracket. Fig. 33 is a view in perspective showing the wear-lugs e¹⁰ e¹¹.

This present invention is carried out as follows:

The case of the machine is preferably made in two parts. (Indicated at A' and A².)

B B denote the driving-shaft, preferably formed of two parts or divided in the center, as shown in the drawings, a crank B' B' 85 being interposed intermediate the outer extremities of the shaft, between the inner ends thereof.

C represents inner feed-disks mounted upon a shaft C', so as to rotate therewith. 90

C² represents outer pressure-feed disks loosely mounted upon a shaft C³, carried by a pressure-arm C⁴. Two feeding-disks are preferably located upon each of the shafts C' and C³ to provide a pair of adjacent feeding-disks— 95 one toward the upper ends of said shafts and another pair toward the lower ends of said shafts. For certain kinds of work these feeding-disks are preferably toothed or milled on their peripheries to more firmly grasp the 100

work and hold it from slipping in the machine. I do not confine myself solely to the use of a double set of feeding-disks, however.

D D' represent the needle-bar, carrying the 5 needle *d* and engaged with the crank B' B' upon the driving-shaft in any suitable manner. The driving-shaft, as above observed, is parted to receive the crank at a point corresponding to the location of the needle-bar 10 where it passes through the case of the machine, at the front and rear thereof. As shown, the needle-bar is constructed with a front portion D and a rear portion D', the rear portion being depressed or offset, as shown, adjacent 15 to the crank, so as to permit the revolution of the crank. The front end of the portion D' of the needle-bar is preferably constructed with a boss *d*', into which the inner end of the part D of the needle-bar is threaded, as 20 shown at *d*², or otherwise connected therewith, a link D² connecting the needle-bar with the crank.

The case of the machine is formed with a suitable guide-bearing, as shown at *a*, for the 25 rear end of the portion D' of the needle-bar. For the inner ends of the driving-shaft B B' suitable boxes are provided, said boxes being preferably constructed of lower portions *a*' and upper portions *a*², provided with 30 bracket-arms, as shown, said arms being united in any proper manner, as by screws *a*³, and secured to the upper and lower portions of the case A' A², respectively, as indicated in detail in Fig. 13. The bracket-arms 35 of these boxes are designed to be so constructed and secured in place that they will be held rigidly and kept from springing, whatever may be the strain thereupon. The parts of the needle-bar are designed, moreover, to be so adjusted that the thrust of the needle-bar to pass the needle through the work will 40 be made just when the crank has passed the center, and will therefore be in position to exert a most powerful force in causing the 45 needle to penetrate the work. Provision is thus made for the amount of power required in heavy work, as in work upon fur robes, heavy leather goods, carpets, heavy canvas, and the like, where a very considerable power 50 is obviously necessary to pass the needle efficiently through the work. It should be understood, however, that the invention is not limited to the specific construction and arrangement of the cranks with the needle-bar 55 and driving-shaft hereinbefore set forth and illustrated in the drawings, inasmuch as the needle-bar may have a crank connection with the driving-shaft in any suitable manner within the scope of this invention.

60 E denotes a looper-bar provided with a looper-arm E', said bar being actuated by a cam E² on the driving-shaft. To this end a lever E³ is provided, actuated by said cam, the cam being provided with a cam-groove *e* and the lever E³ being provided with a roller *e*', projecting into said groove. This lever *e*' is fulcrumed at one end, as shown at *e*², in

any suitable manner, but preferably to a fulcrum-arm *e*³, engaged within the case of the machine. The opposite end of said lever has 70 a jointed connection with a sleeve E⁴ upon the looper-bar, as by a link E⁵, engaged with said sleeve and with said bar. The sleeve E⁴, with the looper-bar passed therethrough, has a vertical movement in the case, as in an 75 elongated opening therein. By this construction and arrangement a vertical movement may be given to the looper-bar to lift and to depress the point of the looper-arm.

The looper-arm is given a rocking movement by means of a lever F, fulcrumed at one end, as at *f*, in any suitable manner, preferably to a fulcrum-arm F', engaged within the case. Said lever F is actuated by the cam E² upon the driving-shaft, said cam being constructed with a cam-groove *f*' and the said lever with a roller *f*², projecting into said groove, the groove *f*' being formed on the opposite face of the cam E² from the groove *e*, the opposite surfaces of the cam E² being 90 shown in Figs. 4 and 6. With the opposite end of the lever F is engaged an elbow-link F², connected with a ball-joint G, carrying the looper-arm in any suitable manner, as by an intervening lever F³. The elbow-link F² 95 preferably has a ball-and-socket joint with the levers F and F³, as indicated at *f*³ and *f*⁴. To this end the adjacent extremities of the levers F and F³ are constructed with sockets, while the extremities of the elbow-link F² are 100 constructed with balls, as shown, said balls being held in said sockets by split collars *f*⁵ and *f*⁶, engaged thereupon and held in place upon the corresponding levers by suitable pins *f*⁷ and *f*⁸ or otherwise, as may be desired. 105

The ball-joint G is preferably formed by socket-plates *g* and *g*', divided longitudinally, said plates inclosing a ball G', through which the looper-bar is passed and keyed, as shown, so that the rocking of the ball in its socket 110 will rock the looper-arm. By separating the socket-plates on a horizontal line it is possible to readily remove the upper plate or cap, permitting the lifting of the whole looper mechanism out of the top of the case and as 115 quickly to replace it, if required.

To give a longitudinal movement to the looper-bar, a slide H is preferably made reciprocatory in guide-recesses of the case, as at *h*. This slide is provided with a downwardly-projecting arm H', actuated by a cam H² on the driving-shaft, said cam being provided, preferably, with a cam-groove *h*' and said arm with a roller *h*², projecting into said groove. Upon the looper-bar E is a bracket-arm E⁶, 125 sleeved upon an oscillatory arm H³. Said arm H³ has a ball-and-socket-joint connection at its extremity with said slide, as shown more particularly in Fig. 5, said arm being provided with a ball and said slide with a corresponding socket to receive the ball end of the arm, as shown, a nut *h*³ engaging the ball end of said arm on the slide. By this construction and arrangement it is evident that the looper-

bar will be reciprocated in the direction of the movement of the slide, while the looper-bar is permitted to rock or oscillate and also to be reciprocated vertically to effect the requisite movement of the looper-arm in forming an overstitch, which movements are well understood and need not be here explained.

In order to get a positive feed of the rolls, I prefer to use a gang-pawl, which may be toothed as closely as the sixty-fourth of an inch, if desired, and whereby the stitch may be lengthened in sixty-fourths of an inch to any desired length by simply turning a suitable adjusting-screw. Accordingly J denotes a gang feed-pawl meshing with a correspondingly-toothed ratchet-wheel C⁶ upon the shaft C'. This feed-pawl J has preferably a jointed connection with an arm J', as indicated at j. The opposite end of the arm J' has a jointed connection, as shown at j', with a spring-barrel J². J² is an adjusting-screw having a threaded engagement in said barrel, as shown in Fig. 3. This barrel is provided with a spring j³, preferably engaged about the adjusting-screw, as shown. Said spring bears against a cap A³, extending about the ratchet-wheel, and tends to hold the spring-barrel, with the arm J', away from the cap, while by means of the adjusting-screw J³ said barrel, with the arm J' and its feed-pawl, may be adjusted in the opposite direction. The arm J' is preferably constructed with a spring-socket, (indicated at j⁸), in which is located a spring J⁴, bearing upon its opposite end upon the spring-barrel to hold the pawl J in contact with the ratchet-wheel. At the side of the barrel I prefer to locate antifriction-rolls j⁵ upon shafts j⁶, which may be covered by a cap a⁴. To automatically actuate said feed-pawl, the cam E² is provided with an antifriction-roll e⁴, projecting from the periphery of the cam to contact with the extremity of the spring-barrel J² upon the rotation of said cam, thereby forcing forward the spring-barrel, and consequently the feed-pawl J, giving a corresponding rotation to the ratchet-wheel.

J⁴ is a locking-pawl preferably gang-toothed to engage with the ratchet-wheel C⁶ and prevent its retraction, a spring j⁶ holding said pawl in contact with said ratchet-wheel. The main case of the machine is provided with an outwardly-projecting feed-case (indicated at A⁴) upon which the cap A³ is engaged, the feed-screw J³ passing through the cap A³. The spring-barrel works in sliding ways a⁵ in the portion of the case A⁴.

To lock the adjusting-screw J³ while the machine is in operation, I provide a lever J⁵, which may be fulcrumed, as indicated at j⁷, upon the cap a⁴, the inner end of the lever being constructed with two or more angular faces to bear against the corresponding faces on the collar J⁶ of the adjusting-screw. J⁷ is a spring to hold the lever J⁵ in normal contact with said collar.

To measure the length of the feed and to render the same visible to the operator, the

cap a⁴ may be provided with a chamber (indicated at a⁸) in which I locate a graduated plate a⁹, which may be graduated to the sixty-fourth of an inch, if desired. The spring-barrel J² carries an index-finger (indicated at j⁸) adjacent to the graduated edge of said plate. Said chamber is closed by a glass (indicated at A⁵) through which the operator may observe the position of the index-finger. To retract the pawls J and J⁴ in case it is desired to reverse the feeding-disks to draw back the work, I provide a slide or bolt C⁷, which carries the spring j⁶, said slide passing through the portion A⁴ of the case, as indicated at a⁸, the inner end passing through a guide-bracket, (indicated at C⁸.) The upper end of the slide C⁷ may be actuated by an eccentric-lever A⁶, fulcrumed to the case of the machine. It will be obvious that when the lever A⁶ is actuated in a proper direction the slide C⁷ will be forced inward, the spring j⁶ carried thereby being carried past the fulcrum of the pawl J⁴, thereby tripping said pawl, the inner end of the slide C⁷ being carried against the arm J' to depress said arm, and thereby retract the pawl J from the ratchet-wheel, thus releasing the feed-ratchet entirely. The cap a⁴ may be held upon the portion A⁴ of the case by means of screws a⁹. The cap A³ may be held in place by means of screws a¹⁰. The upper portion A² of the case is constructed with a recess (indicated at A⁷) in which the pressure-arm C⁴ is carried. Fig. 100 more particularly shows the manner of dividing the portions A' A² of the case on the line of the shaft of the needle-bar and the driving-shaft, the case being formed with suitable openings (indicated at A⁸ and A⁹) for said shafts, respectively. The two parts of the case may be bolted together, as by bolts, (indicated at A¹⁰.) The lower socket-plate g is preferably cast integral in the upper portion of the case. The antifriction-rolls j⁵ can be mounted upon screw-journals.

The shaft C' may be journaled at its lower end in a bracket A¹¹. Said bracket is formed with a collar a¹¹, with which an adjusting-cap A¹² has a threaded connection, said cap carrying a pin A²², having a hardened cone-shaped head, upon which rests the lower end of the shaft C'. The cap A¹² is split at its threaded portion, as indicated at a¹². Said cap is held in place by a lock-nut A¹³. The lock-nut and the outside threaded portion of the cap A¹² have corresponding beveled adjacent faces permitting a desired adjustment of the cap, and consequently the desired adjustment of the shaft C', the said cap being held in adjusted position by tightening said lock-nut.

When it is desired to dispense with the lower disks C C², suitable washers may be put upon the corresponding shafts in place thereof. The portions A' A² of the case are constructed with split journal-bearings, (indicated by the numerals 1 and 2,) over which is engaged a locking-sleeve 3, having a threaded engagement thereupon to hold the portions of

the bearing in firm position. A hand-wheel 4 is located upon one end of the driving-shaft and the opposite end may be connected with any suitable driving device. In Fig. 2 is shown a grooved pulley 5, which may be attached to any additional hand-wheel 6. In Fig. 5 is shown a cone-pulley 7. The case of the machine is provided with a cap 8. The inner end of the pressure-arm C⁴ is formed with a spring-chamber 9, in which is located a spring 10, the tension of the spring being adjusted by a hand-screw 11. I prefer to make the arm C⁴ of malleable iron, and in order to properly anneal it it will be understood that the walls of the spring-barrel should be of nearly equal thickness, which may be done by forming the barrel in the upper portion thereof as shown, and by recessing and ribbing the lower portion, as indicated at 12. To release the pressure of the bar C⁴, a bell-crank 13 may be provided connected by a rod 14 with a foot-lever 15. To adjust the arm C⁴ or to take up any lost motion by reason of wear, I prefer to provide a wearing-plate 16 and screws 47, having an adjustable bearing thereagainst. I prefer to hold the bracket-arm E⁶ upon the looper-bar by means of collars e⁵ and e⁶, secured upon the looper-bar, as by set-screws e⁷. (Shown in Fig. 1.) The sleeve E⁴ is preferably constructed with an eye at e⁸ to receive a link-pin e⁹, connecting the link E⁵ with said sleeve. Said sleeve is also preferably constructed with guide and wearing lugs e¹⁰ outside the case and similar lugs e¹¹ inside the case of the machine to guide the looper-bar in its vertical reciprocation. The looper-bar is sleeved through the ball G and keyed therein, as indicated at e¹². To provide for a desired tension upon the thread in the backward action of the needle-bar in order to form the required loop for the looper-arm to catch in forming the loop, I prefer to employ a pin D³, engaged in the needle-bar, as shown in Fig. 2, between the head of which and the adjacent surface of the needle-bar the thread 19 is fed, a spring D⁴ being recessed into the side of the needle-bar, and said spring being constructed with a depression near its rear portion as shown at d³. The separable bearing 17 of the needle-bar, which bearing is formed upon the case of the machine, is provided with an anti-friction-roll 18, which may be located between the parts of the separable bearing. The pin is constructed with a slot, as at 58, in which the end of the spring D⁴ is loosely engaged, until as the needle-bar recedes and the roller 18 rides into said depression d³ the end of the spring is permitted to exert its tension upon the pin at the end of the slot to hold the thread firmly between the head of the pin and the needle-bar, thus insuring the formation of said loop to form the stitch. In locating the driving-shaft and needle-bar on the same plane it is possible to shorten and lighten various parts of the machine, and thereby make the parts compact and easily accessible, also to shorten the case of the machine, thus

saving considerable weight and cost in the construction of the machine-case. Furthermore, by locating the ball-bearing of the looper-bar on the inside of the machine and constructing the various portions of the machine so that the looper-bar may be lifted out of the case I have simplified the construction very materially and the means of attaching and operating the machine. Thus the looper mechanism may be taken out of the case with but little disarrangement of the parts and so keep them largely intact. So, also, I have thus made it possible to put a larger proportion of the operating parts of the machine on the inside of the case than has been common heretofore. Obviously, the part of the case of the machine on the line of the driving-shaft and needle-bar greatly facilitates the adjustment of the various parts of the machine, inasmuch as the parts can be put together so that they may be easily shifted and adjusted, the parts being readily accessible by removing the upper portion of the case. This construction is a great aid in putting the machine together and in making any repairs as well as any adjustment that may be necessary. To firmly hold the two edges of the work together in the operation of being sewed, as when it is desired to accurately match the figures of a carpet, and therefore to hold the two edges of the work in fixed position without liability of the figures being mismatched, any suitable means may be employed, as a clamping device 27, (shown in detail in Fig. 30,) constructed of clamping-arms 28 and 29, pivotally connected, as at 30, said arms provided with a tension-spring 31 to close the jaws 32 from the work. Where it is desired to form a folded seam also, this clamping device 27 may be employed to hold the parts together.

In Fig. 20 I show a hand-power machine with a movable platform to carry heavy work, such as carpet, sails, &c. In this case an auxiliary driving-shaft B⁴ is provided upon a supporting-frame B³, said shaft having a bevel-gear b⁴, a hand-crank B⁵ being also provided, having a gear b⁵ meshing with the gear b⁴. Upon the main driving-shaft B is located a sprocket-wheel. (Indicated in dotted lines in Fig. 20, as at b⁶.) The shaft B⁴ is provided with a balance-wheel B⁶ and with a sprocket-wheel, (indicated at B⁷,) a sprocket-chain B⁸ connecting the sprocket-wheels b⁶ and b⁷.

Heretofore the customary method of operating carpet-sewing machines has been to move the machine over or along the work, the work remaining stationary. The seam has also heretofore been formed with a through-and-through stitch leaving a seam or welt on one side of the carpet, which has prevented the carpet from being pulled out and laid flat on the floor, but always leaving a ridge along the line of the same. My invention contemplates a reversal of the order of arrangement and provides a traveling platform to carry the work, the machine being stationary, while I also provide means for securing an overseam

stitch, allowing the seam to pull out so that the two adjacent parts of the carpet will lie flat edge to edge, the carpet lying flat upon the floor. Obviously these provisions constitute very desirable features and improvements upon existing methods and devices and operations in sewing carpets and analogous work. To carry the work in cases of this description, L denotes a movable platform mounted upon trucks L', having ball-bearings in the wheels of the truck to afford the greatest amount of ease in the movement of the platform. My invention contemplates providing a platform sufficiently large to allow for folding up and carrying carpets of any reasonable dimensions in the operation of the sewing. My improved platform is provided, preferably, with upright standards L² on the back and at the front with curved standards L³, hinged at their lower ends to corresponding brackets L⁴ upon the platform, as by means of hinged bolts L⁵. Upon each of said brackets is a ratchet L⁶, while the standards L³ are provided each with a pawl L⁷. Upon the upper end of each of the standards L³ is a clamping-jaw l, jointedly connected therewith, as shown at l', to grip against the work, the corresponding standard L² upon the opposite side of the work being provided with a corresponding clamping-jaw l', the work being held between the corresponding jaws l and l'. The standards L³ are each formed with a socket l⁸, in which may be engaged an operating-lever l⁹, whereby when the corresponding pawl L⁷ is released the corresponding standard L³ may be moved away from the work, permitting the work to be lifted off and away from the platform. At the ends of the platform and arranged in the line of the work are additional oscillatory standards L⁸, supported upon the platform essentially in the same manner as the standards L³. Said standards L⁸ are provided at their upper ends with gripping-jaws to engage the ends of the work in order that the work may be properly stretched, standards L⁸ swinging, essentially, at right angles to the standards L³. Said jaws may be formed with a stationary jaw l¹⁰, bolted to the standard in a position to allow it to pass under the feed-rolls. A corresponding clamping-jaw l¹¹ is also provided, a link l¹² having a connection at one end with a bracket l¹³, attached to the standard L⁸, as shown at l¹⁴, said link having a jointed connection with the jaw l¹⁰ at its opposite end, as indicated at l¹⁵. The standard L⁸ is also provided with additional clamping-jaws projecting above the jaws already described to engage the work at or near the upper edges thereof and in order that the work may be properly stretched along the line for the stitching. This clamping-jaw may consist of a jaw 33, formed integrally with a supporting-arm 34, having a jointed connection at its lower end, as indicated at 35, upon the corresponding standard L⁸. An additional jaw 36 is hooked into an opening, (indicated in dotted lines at 37, Fig. 21,) said jaw 36 be-

ing provided with a clamping-bolt 38, passed therethrough, one end of said bolt provided with a ball end 39, having a corresponding socket engagement with the jaw 33, as indicated at 40, said bolt being held in place by a hand-nut 41. The jaw 36 is recessed to receive a spring 42, which keeps the jaw normally open, the jaw 36 being closed by manipulating the hand-nut 41. This open clamping device just described may be dropped entirely out of the way by means of the jointed connection at 35. To give additional tension to this open clamping device, if desired, the arm 34 may be provided with a hand-screw 42, bearing against the upper end of the standard L⁸. The bases of the standards L⁸ are connected with the platform, in consequence of which obviously the clamping-jaws already described could only engage the work of a length corresponding to the distance of said standards apart. To provide for different lengths of carpet or other work, my invention contemplates the employment of a separable clamping device, (shown in detail in Fig. 31,) in which clamping-jaws 43 and 44, actuated by a bolt 45, a nut 46 thereupon, and a spring 48, are employed, constructed, and arranged in a similar manner to the clamping device shown in Fig. 22, except that the jaw 43 instead of being supported upon an arm 34 is in this instance provided with an eye, as at 49, through which a suitable strap 50 may be engaged, said strap being engageable in the upper clamping device upon one of the standards L⁸ at the opposite end. This will obviously provide for the proper stretching of the work whatever may be the length of the seam to be sewed. The platform L is supported upon the axle L⁹ of the truck in any suitable manner, as by bracket-bearings L¹⁰. The truck-wheels are indicated at M, said wheels traveling upon suitable tracks, (indicated at M').

To actuate the platform and cause it to travel with proper speed as the carpet or other work is being fed through the feeding-disks, I lengthen the shaft C', upon which the inner feed-disks are located where the platform is employed in connection with the machine, said shaft having a bearing in a fixed standard C¹, the base of said standard preferably being socketed to receive the lower end of the shaft, as shown at c, a cone-shaped pin c' being engaged in said standard to support the lower end of said shaft. Upon the shaft I engages a pinion (indicated at C¹⁰) provided with a hub c², said pinion being constructed with the same diameter as the ratchet-wheel C⁶ and said pinion meshing with a rack-bar 51 upon the inner edge of the platform L. With the hub c² of the pinion is engaged a yoke c³, connected with an operating-lever c⁴. The yoke c³ may be made separable from said lever or integral therewith, as may be preferred. Any suitable means may be provided to actuate the lever C⁴. Said lever is preferably weighted, as shown at c⁵, so as to hold

the pinion in normal engagement with said rack. When it is desired to throw the pin out of mesh with the rack, as when it is desired to move the platform independently of the machine, it may be done, obviously, by a suitable manipulation of the lever c^4 , throwing downward said pinion out of mesh with said rack-bar. In Fig. 20 I show an eccentric (indicated in dotted lines at c^6) actuated by a crank c^7 , by means of which the lever c^4 may be lifted at its outer end to depress the pinion upon its shaft. As shown in Fig. 26, a separable foot-lever c^8 may be employed, projecting underneath the lever c^4 , by means of which said latter lever may be lifted. It will be seen that by throwing said pinion out of gear and at the same time throwing the gang-pawls engageable with the ratchet-wheel C^6 out of engagement therewith in the manner hereinbefore described the work and the platform may be moved in either direction, as may be desired. Such a movement would be necessary in a case of breakage of the thread, for example, as well as under other circumstances.

I prefer to unite the standards L^3 to their bracket-bases, as more particularly shown in detail in Fig. 32, the bracket L^4 being constructed with a hub L^{11} , upon which the lower end of the corresponding standard L^3 is sleeved. Upon the bolt L^5 is a retaining-nut L^{11} , with an intervening washer L^{12} .

The standards L^3 are preferably engaged upon their corresponding bracket-bases L^4 by bifurcating the lower ends of said standards and locating them astride the rib, upon the periphery of which is formed the ratchet L^6 . This is more particularly shown in Fig. 24. In this case a tubular bearing L^3 is provided about the bolt L^5 to provide a stiffened bearing and also a removable wearing-bearing.

Where the traveling platform is employed, the sewing-machine may be supported upon any suitable frame B^3 . The provision of the sprocket mechanism obviously provides a positive and powerful hand driving device of sufficient power to drive the machine and the traveling platform.

To hold the needle firmly in place upon the needle-bar D , I prefer to construct the needle-bar with a hinged lip or wing d^4 , having a jointed connection with said bar, as indicated at d^5 , a screw-pin being employed to form the hinge. The hinged lip d^4 is clamped upon the needle d by means of a screw d^6 .

By holding the work in the manner described and sewing it by an overseaming stitch the carpet can readily be pulled out and laid flat and even on the floor without any welt or ridge at the seam.

What I claim as my invention is—

1. In a sewing-machine, the combination with a driving-shaft, of a needle-bar, a link connecting the needle-bar with the driving-shaft, said needle-bar formed in two parts having a threaded engagement the one with

the other, one of said parts recessed to permit the revolution of the crank, and forked to engage the adjacent end of the link, for the purpose set forth.

2. In a sewing-machine, the combination of a driving-shaft parted intermediate its ends and having its bearings in the case toward the outer ends of said shaft, a needle-bar having crank-arms connected therewith and with the inner ends of the shaft, and additional bearings at the inner ends of the shaft and adjacent to the crank-arms and on each side thereof supporting the crank-arms and the inner ends of the driving-shaft, substantially as set forth.

3. In a sewing-machine, the combination of a driving-shaft, and a case separable on the line of the driving-shaft, a looper-bar, a ball through which the looper-bar is sleeved, and a separable case for said ball projecting inward from the case of the machine, for the purpose set forth.

4. In a sewing-machine, the combination of a case cut away on one of its exterior lateral faces, a pressure-arm having a reciprocatory movement in said cut-away portion of the case, and means engaged upon the lateral face of the case to hold said arm in engagement in said cut-away portion, for the purpose set forth.

5. In a sewing-machine, the combination of a case cut away on one of its exterior lateral faces, a pressure-arm having a reciprocatory movement in said cut-away portion of the case, means engaged upon the lateral face of the case to hold said arm in said cut-away portion, and means to adjust said arm to take up lost motion occasioned by wear, for the purpose set forth.

6. In a sewing-machine, the combination of a looper-bar provided with a bracket-arm, a slide, an arm sleeved into said bracket-arm and having a ball-and-socket engagement with said slide, said slide provided with a cap-nut engaged over said ball-and-socket joint, for the purpose set forth.

7. In a sewing-machine, the combination with a looper-arm, of a bracket-arm sleeved thereupon, collars secured to the looper-arm to hold said bracket-arm in place and permit a free movement of said bracket-arm, a slide, and an arm sleeved into said bracket-arm and having a ball-and-socket engagement with said slide, for the purpose set forth.

8. In a sewing-machine, the combination of a case, a looper-bar, means to operate the looper-bar, and a sleeve located upon said bar, said sleeve formed with guide and wearing lugs adjacent to the case, substantially as set forth.

9. In a sewing-machine, the combination of a looper-bar, a ball-and-socket joint through which said bar is sleeved and keyed, a lever to rock said ball-joint having a fulcrumed engagement at one extremity thereof, an elbow-link having a ball-and-socket joint at one end with said lever, an additional lever

- engaged with the ball-joint of the looper-arm and with which the elbow-link has a ball-and-socket-joint connection, substantially as set forth.
- 5 10. In a sewing-machine, the combination of a looper-bar, a ball-and-socket joint through which said bar is sleeved and keyed, a lever to rock said ball-joint having a fulcrumed engagement at one extremity thereof, an elbow-link having a ball-and-socket-joint connection at one end with said lever, an additional lever engaged with the ball-joint of the looper-arm and with which an elbow-link has a ball-and-socket-joint connection, said elbow-link provided with balls at its extremity engaged in corresponding sockets in the corresponding levers, split collars securing said balls in place, and means to lock said collars in position, for the purpose set forth.
- 10 15 20 25 30 35 40 45 50 55 60 65 70 75 80 85 90 95 100 105 110 115 120 125 130
11. In a sewing-machine, the combination of a pair of upper feeding-disks, a pair of lower feeding-disks, and a holding device to hold the work together located underneath the lower pair of feeding-disks, substantially as set forth.
12. In a sewing-machine, the combination of a feeding-disk, a shaft carrying the disk, a ratchet-wheel upon said shaft, a gang-toothed pawl to drive said ratchet-wheel, a movable barrel, means to move said barrel, an arm having a fulcrum connection with the pawl and with the barrel, an adjusting-screw engaged with said barrel and with the case of the machine to adjust said movable barrel, and a spring to hold the pawl in normal engagement with the ratchet-wheel, substantially as set forth.
13. In a sewing-machine, the combination of a feeding-disk, a shaft carrying the disk, a ratchet-wheel upon said shaft, a gang-toothed pawl to drive said ratchet-wheel, a movable barrel, means to move said barrel, an adjusting-screw engaged with said barrel and with the case of the machine to adjust said movable barrel, and means connecting the gang-toothed pawl with said movable barrel, said movable barrel having a reciprocatory movement within the case of the machine, for the purpose set forth.
14. In a sewing-machine, the combination of a feeding-disk, a driving-shaft carrying the disk, a ratchet-wheel mounted on the shaft, a gang-toothed pawl to drive the ratchet-wheel, a reciprocatory barrel, means to reciprocate said barrel, antifriction - rollers adjacent to said barrel, means to adjust said barrel, and means connecting the gang-toothed pawl with said barrel, for the purpose set forth.
15. In a sewing-machine, the combination of a feeding-disk, a shaft carrying the disk, a ratchet-wheel mounted on the shaft, a gang-toothed pawl to drive the disk, a gang-toothed pawl to prevent the retraction of the disk, a slide to simultaneously retract said pawls, and a lever to actuate said slide, substantially as set forth.
16. In a sewing-machine, the combination of a feeding-disk, a shaft carrying said disk, a ratchet-wheel mounted on said shaft, a gang-toothed pawl to drive said ratchet-wheel, a gang-toothed pawl to prevent the retraction of the ratchet-wheel, a yielding arm to actuate the driving-pawl, a slide provided with a spring bearing upon the retaining-pawl, and means to actuate said slide to simultaneously release said pawls from the ratchet-wheel, substantially as set forth.
17. In a sewing-machine, the combination of a feeding-disk, a shaft carrying the disk, a ratchet-wheel upon the shaft, a gang-toothed pawl to drive the ratchet-wheel, an adjustable reciprocatory barrel, an oscillatory spring-actuated arm fulcrumed at one end to said barrel and reciprocatory therewith to normally hold the pawl in engagement with the ratchet-wheel with which arm said pawl has a fulcrumed connection at the opposite end thereof, means to retract the oscillatory arm to disengage the pawl, an adjusting device to adjust said barrel, an indicating device adjacent to the adjusting device to indicate the adjustment of the pawl, and means to automatically reciprocate said barrel, substantially as set forth.
18. In a sewing-machine, the combination of a feeding-disk, a shaft carrying the disk, a ratchet-wheel upon the shaft, a gang-toothed pawl to drive said ratchet-wheel, an adjustable reciprocatory barrel, an oscillatory spring-actuated arm to carry the pawl and normally hold the pawl in engagement with the ratchet-wheel fulcrumed to said barrel and reciprocatory therewith, means to retract the oscillatory arm to disengage the pawl, an adjusting device to adjust said barrel, an index-plate, a traveling pointer carried by said adjusting device adjacent to said plate, and means to automatically reciprocate said barrel, substantially as set forth.
19. In a sewing-machine, the combination of a feeding-disk, a shaft carrying the disk, a ratchet-wheel mounted upon the shaft, a gang-toothed pawl to drive the ratchet-wheel, an oscillatory and reciprocatory arm to carry the pawl, an adjustable barrel carrying said arm, a stationary index-plate, a traveling pointer carried by said barrel adjacent to said plate, and a transparent covering inclosing said plate, for the purpose set forth.
20. In a sewing-machine, the combination of a feeding-disk, a shaft carrying the disk, a ratchet-wheel mounted on the shaft, a gang-toothed pawl to drive said ratchet-wheel, an adjustable barrel carrying said driving-pawl, a chambered cap located over a portion of said barrel, a stationary index-plate located in the chamber of the cap, a pointer carried by said barrel adjacent to said plate, and a transparent covering for said chamber, for the purpose set forth.
21. In a sewing-machine, the combination of a feeding-disk, a shaft carrying the disk, a ratchet-wheel mounted on the shaft, a gang-toothed pawl to drive the ratchet-wheel, a re-

ciprocatory barrel carrying the pawl, a driving-shaft, a cam upon the driving-shaft provided with a roller on its periphery to contact with said barrel upon the revolution of the cam to actuate the ratchet-wheel, substantially as set forth.

22. In a sewing-machine, the combination of a feeding-disk, a ratchet-wheel to actuate the disk, a pawl to engage the disk, an adjustable device carrying said pawl, an adjusting-screw to adjust said device, and a spring-actuated lever to lock said adjusting-screw, substantially as set forth.

23. In a sewing-machine, the combination of a feeding-disk, a shaft carrying the disk, a bearing carrying the lower end of the shaft, a cap interiorly and exteriorly threaded at one extremity thereof and having a threaded engagement with said bearing, and a lock-nut, said threaded portion of the cap being split, and said lock-nut and the adjacent portion of the cap having a beveled engagement the one with the other, substantially as set forth.

24. In a sewing-machine, the combination with a needle-bar, of a spring extending longitudinally of the bar provided with a depression toward its rear end, a sliding transverse pin located in said bar and loosely engaging said spring, the head of the pin in contact with the needle-bar gripping the thread therebetween when the tension of the spring is exerted on the pin, and a roller adjacent to said spring, said spring exerting its tension upon said pin upon the retracted movement of said needle-bar, substantially as set forth.

25. In a sewing-machine, the combination with a needle-bar, of a spring extending longitudinally of the bar having a recessed engagement in the needle-bar and formed with a depression toward its rear end, a transverse pin extending through said bar to form a thread tension device, and a roller located adjacent to the outer face of the spring, the spring exerting its tension upon said pin upon the retraction of the needle-bar permitting the roller to enter said depression in the spring, substantially as set forth.

26. In a sewing-machine, the combination of rotatable feeding-disks, a ratchet-wheel to drive said disks, a truck, a traveling platform upon said truck provided with a rack, and a pinion upon the shaft of the feeding-disks meshing with said rack, said pinion and said feeding-disks being of the same diameters, for the purpose set forth.

27. In a sewing-machine, the combination of feeding-disks, a traveling platform, means to synchronously drive said machine and actuate said platform and said disks, said platform provided with a rack and the shaft of the feeding-disks with a movable pinion to mesh with the rack, and means to throw the pinion out of mesh with the rack, for the purpose set forth.

28. The combination of a sewing-machine provided with feeding mechanism, a traveling platform provided with upwardly-project-

ing standards at opposite ends and at opposite sides having clamping-jaws at their upper ends to engage the work, and means to synchronously drive the feeding mechanism and the platform, for the purpose set forth.

29. The combination with a sewing-machine provided with feeding-disks, of a traveling platform, means to actuate the feeding-disks and the platform, and clamping devices supported upon the platform and to clamp and stretch the work, said clamping devices arranged to pass under and clear of said feeding-disks, substantially as set forth. 80

30. The combination with a sewing-machine provided with feeding mechanism, of a traveling platform, means to drive the platform, said machine and platform provided with means to laterally clamp portions of the work together, and said platform provided with additional means to clamp and stretch the work longitudinally thereof, for the purpose set forth. 85

31. The combination with a sewing-machine provided with feeding mechanism, of a traveling platform, means to drive the platform and a device carried by the platform provided with clamping mechanisms at different elevations to clamp and stretch the work, for the purpose set forth. 90

32. The combination with a sewing-machine provided with feeding mechanism, of a traveling platform, means to drive the platform and standards carried by the platform having clamping devices, said standards provided with additional clamping devices to clamp and stretch the work, for the purpose set forth. 100

33. The combination with a sewing-machine provided with feeding mechanism, of a traveling platform, means to drive the platform and standards carried by the platform, said standards provided with rigid clamping devices to engage the work, and with additional clamping devices having a jointed engagement with the standard to engage the work, for the purpose set forth. 105

34. The combination of a sewing-machine provided with feeding mechanism, a traveling platform, means to drive the platform standards carried by the platform, clamping devices carried by said standards and arranged to pass under and clear from the feeding mechanism, and additional clamping devices jointedly supported upon said standards to engage the work, and whereby the additional clamping devices may be swung out of the way of the feeding mechanism, for the purpose set forth. 115

35. The combination with a sewing-machine provided with feeding mechanism, of a traveling platform, means to drive the platform, clamping devices carried by the platform to engage and stretch the work longitudinally thereof, and additional clamping devices to engage the work, for the purpose set forth. 125

36. The combination with a sewing-machine provided with feeding mechanism, of a traveling platform, means to drive the platform,

and upwardly-extending standards carried by the platform at opposite sides and at opposite ends thereof provided with clamping devices to clamp the work, the standards at the outer side of the platform having a jointed engagement at their lower ends upon the platform, for the purpose set forth.

37. The combination with a sewing-machine provided with feeding mechanism, of a traveling platform, means to drive the platform, rigid standards supported upon the inner side of the platform toward its edge adjacent to the machine and at opposite ends thereof, and curved standards supported toward the outer edge of the platform having a jointed engagement at their lower ends upon the outer side of the platform, said standards separated at their lower ends and provided with means to engage and support the work, substantially as 20 and for the purpose set forth.

38. The combination with a sewing-machine provided with feeding mechanism, of a traveling platform means to drive the platform, rigid standards supported upon said platform toward its inner edge, swinging standards supported toward the outer edge of the platform, and additional swinging standards supported toward each end of the inner edge of said platform, the swinging standards of the outer 30 edge of the platform and the swinging standards of the inner edge of the platform made oscillatory at essentially right angles the one to the other, for the purpose set forth.

39. The combination with a sewing-machine provided with feeding mechanism, of a traveling platform, and means to drive the platform, standards to clamp the work supported upon the platform having a jointed connection upon the platform, said platform and 40 standards provided with pawl-and-ratchet mechanism, for the purpose set forth.

40. The combination with a sewing-machine provided with feeding mechanism, of a traveling platform to hold and carry the work, means to drive the platform, rigid standards at the inner edge of the platform and at opposite ends thereof, outer standards jointedly supported upon the outer edge of the platform, and lever mechanism to actuate said 45 outer standards, said standards separated at their lower ends, for the purpose set forth.

41. The combination with a sewing-machine provided with feeding mechanism, of a trav-

eling platform to hold and carry the work, means to drive the platform, an outer standard provided with a clamping device to clamp the work jointedly supported toward the outer edge of said platform, and an inner rigid standard upon said platform coöperating with the outer standard, said platform provided 55 with a supporting base or bracket upon which said standard is jointedly engaged, said base or bracket provided with a hub upon which the lower extremity of the standard is sleeved, for the purpose set forth. 65

42. The combination with a sewing-machine provided with feeding mechanism, of a traveling platform to hold and carry the work, means to drive the platform, outer clamping-standards supported upon the platform toward the 70 outer edge and at the extremities thereof, and inner rigid standards upon said platform coöperating with the outer standards, said platform provided with a supporting base or bracket with which the standards are jointedly engaged, said standards each bifurcated toward its lower end and engaged astride a portion of said base, a hinge-pin to engage the bifurcated portion of the standard with said portion of the base, and a tubular wearing- 80 bearing about said hinge-pin, for the purpose set forth.

43. The combination with a sewing-machine provided with inner and outer feeding-disks, of a shaft carrying the inner disks, a traveling platform to support and carry the work, a bearing adjacent to the platform carrying the lower end of said shaft, and means connected with the shaft to actuate the platform, substantially as set forth. 90

44. The combination with a sewing-machine, of a traveling platform to hold the work, means to drive said platform, standards carried at the inner side of said platform, swinging standards also carried at the inner side 95 of said platform and toward the extremities thereof provided with clamping mechanism, and outer standards coöperating with the first-named standards to clamp the work, substantially as set forth. 100

In testimony whereof I sign this specification in the presence of two witnesses.

SOLON G. HOWE.
